US0D1043050S

(12) **United States Design Patent** (10) **Patent No.:** **US D1,043,050 S**
(45) **Date of Patent:** **** Sep. 24, 2024**

(54) **HEADBAND**

(71) Applicant: **Shenzhen Jueyier Technology Co., Ltd.**, Shenzhen (CN)

(72) Inventor: **Xiulian Chen**, Fujian (CN)

(**) Term: **15 Years**

(21) Appl. No.: **29/883,094**

(22) Filed: **Jan. 24, 2023**

(51) **LOC (14) Cl.** **02-03**

(52) **U.S. Cl.**

USPC **D2/865**

(58) **Field of Classification Search**
